UNITED STATES PATENT OFFICE

159,488

BUFFET

Leo Jiranek, New York, N. Y., assignor to Heywood-Wakefield Company, Gardner, Mass., a corporation of Massachusetts

Application July 29, 1948, Serial No. 147,836

Term of patent 3½ years

(Cl. D33—13)

To all whom it may concern:

Be it known that I, Leo Jiranek, a citizen of the United States, residing at New York, in the county of New York and State of New York, have invented a new, original, and ornamental Design for a Buffet, of which the following is a specification, reference being had to the accompanying drawing, forming part thereof, in which:

Fig. 1 is a view in perspective of a buffet, showing my new design.

Fig. 2 is a view in front elevation of the buffet shown in Fig. 1, on a reduced scale.

Fig. 3 is a view in end elevation of the buffet shown in Fig. 1, on the same scale as Fig. 2.

Fig. 4 is a plan view of the buffet shown in Fig. 2.

I claim:

The ornamental design for a buffet, substantially as shown.

LEO JIRANEK.
